UNITED STATES PATENT OFFICE.

JOHN H. VICTOR, OF CHICAGO, ILLINOIS, ASSIGNOR TO VICTOR MANUFACTURING & GASKET CO., A CORPORATION OF ILLINOIS.

DESIGN FOR A SHEET PACKING RACK.

Application filed March 23, 1927. Serial No. 21,283. Term of patent 14 years.

To all whom it may concern:

Be it known that I, JOHN H. VICTOR, a citizen of the United States, residing at Chicago, in the county of Cook and State of Illinois, have invented a new, original, and ornamental Design for Sheet Packing Racks, of which the following is a specification, reference being had to the accompanying drawing, forming part thereof.

The essential feature claimed herein is the base or foot portion as illustrated in Figure 2.

Figure 1 is a perspective view of a sheet packing rack.

Figure 2 is a side elevation showing the essential feature of applicant's design, namely, the base or foot portion of a sheet packing rack.

I claim:

The ornamental design for a sheet packing rack as shown and described.

In testimony whereof I affix my signature at 10 South La Salle Street, Chicago, Illinois.

JOHN H. VICTOR.
